TOY GUN

Talley Webber Nichols, Jacksonville, Tex.

Application April 3, 1957, Serial No. 45,570

Term of patent 14 years

(Cl. D34—15)

Fig. 1

Fig. 2

Fig. 3

Fig. 1 is a side elevational view of a toy gun, showing my new design, the opposite side having substantially the same appearance;

Fig. 2 is a top plan view; and

Fig. 3 is a front elevational view thereof.

I claim:

The ornamental design for a toy gun, as shown and described.
